United States Patent Office

Des. 204,441
Patented Apr. 12, 1966

204,441

CENTER SET FAUCET FIXTURE

Homer M. Harvey, Los Angeles, and Dale H. Hart, Long Beach, Calif., assignors to Harvey Aluminum (Incorporated), Torrance, Calif., a corporation of California

Filed Nov. 2, 1964, Ser. No. 82,421

Term of patent 14 years

(Cl. D91—3)

FIG. 1.

FIG. 2.

FIG. 3.

FIG. 4.

FIG. 5.

FIG. 1 is a perspective view taken from the front, top and one side of the center set faucet fixture embodying our new design.

FIG. 2 is a front view of the fixture.

FIG. 3 is a top view of the fixture.

FIG. 4 is a side view showing the other side of the fixture, and

FIG. 5 is a rear view of the fixture.

The dominant features of our design reside in the portions in full lines.

We claim:

The ornamental design for a center set faucet fixture, as shown and described.
